CLAIM

The ornamental design for a computer screen with graphical user interface, as shown and described.

DESCRIPTION

1. Computer screen with graphical user interface
1.1: is a Front view of the computer screen with graphical user interface showing our new design;
1.2: is a Top view thereof;
1.3: is a Right view thereof.
 The broken lines illustrate the computer screen and form no part of the claimed design. The other broken lines illustrating the computer is for environmental purposes and form no part of the claimed design. The broken lines illustrate portions of the graphical user interface and form no part of the claimed design.

1 Claim, 3 Drawing Sheets(56)
